ATTORNEY

UNITED STATES PATENT OFFICE

WILLIAM K. MORRISON, OF CHULA VISTA, CALIFORNIA

FENCE

Application filed August 20, 1930. Serial No. 476,511.

My invention relates to fences, and the objects of my invention are:

First: To provide a fence which may be economically formed of sheet metal;

Second: To provide a fence of this class in which the fence post and fence rails may be formed of sheet metal, as well as the fence itself;

Third: To provide a fence of this class which, though formed of sheet metal, permits ready passage of air therethrough, the fence being foraminous;

Fourth: To provide a fence of this class which, though reinforced or stiffened, does not require corrugations for this purpose or other means which tend to shorten or reduce the area of the fence;

Fifth: To provide a novel means of securing the rails and fence posts to a fence of this class;

Sixth: To provide a novel means of supporting the fence relative to the ground, in which the fence may be positioned before the support therefor is placed;

Seventh: To provide a fence of this class, in which the fence posts form a guide means for the fence supports or stakes;

Eighth: To provide a fence of this class, in which the fence posts may be mounted obliquely across the fence, whereby the fence rails may be omitted; and

Ninth: To provide on the whole a novelly constructed fence which is simple of construction, proportional to its functions, durable, efficient and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon, which form a part of this application, in which:

Figure 1 is a fragmentary elevational view of my fence; Fig. 2 is a slightly enlarged fragmentary sectional view thereof through 2-2 of Fig. 1; Fig. 3 is a fragmentary de-

veloped view of the fence; Fig. 4 is an enlarged fragmentary elevational view of my fence with an added stiffening means; Fig. 5 is a sectional view thereof through 5-5 of

Fig. 4; Fig. 6 is a fragmentary plan view of my fence taken from 6-6 of Fig. 1; Fig. 7 is a further enlarged fragmentary sectional view substantially through 7-7 of Fig. 1;

Fig. 8 is a fragmentary elevational view of my fence structure with the fence posts arranged diagonally thereon; and Fig. 9 is an enlarged fragmentary sectional view

through 9-9 of Fig. 8.

Similar characters of reference refer to similar parts and portions throughout the several views of the drawings;

Fence 1, vertical posts 2, rails 3, adapters 4, bolts 5, inclined posts 6 and stake members 7 and 8 constitute the principal parts and portions of my novel fence.

The fence is formed of sheet metal. In it are formed a plurality of equally spaced holes 1a, preferably square holes or at least polygonal in shape. The holes are formed by first cutting intersecting slits as shown in

Fig. 2, and then bending the four triangular flaps 1b thus formed outwardly at right angles to the plane of the fence, thus forming a plurality of independent reinforcing ribs which extend outwardly from the one

face of the fence. The several holes are preferably arranged in rows running at right angles to each other, and at the intersection of the several rows there may be provided raised portions 1c in the form of crosses, as

shown in Figs. 4 and 5. These serve to increase the stiffness of the fence.

The fence is supported by a plurality of fence posts 2. Each fence post comprises a pair of parallel disposed strip portions 2a, the distance between their centers being

equal to centers between alternate vertical rows 1b of the fence. These strip portions 2a are separated by a channel portion 2b.

The strip portions are provided with a plurality of equally spaced polygonal sided openings 2c, having the same number of sides as the openings 1a. These are formed in the same manner as the openings 1a, that is, by first forming radiating slits in the form

70

85

95

100

of a cross or star, and then bending the triangular flaps thus formed outwardly at right angles to the surface of the material. These openings 2c are adapted to coincide with the openings 1a in the fence 1 so that the reinforcing or ear portions 2c of the side strips 2a can fit within the corresponding portions 1b, as shown best in Figs. 6 and 7, thus, 10 spacing the side strips 2a outwardly from the surface of the fence 1.

Along the extreme edges of the side strips 2a, there may be provided rib portions 2e in the form of low walls, which extend through the fence 1 in such a manner as to fit 15 between the adjacent vertical rows thereof, as shown best in Figs. 1 and 6.

The fence rails 3 are identical in construction to the posts 2; in fact, the material used for rails or posts may be made in lengths 20 suitable for rails and then cut to form the fence posts, or in cases where the rails are not needed, the material may be cut to the length of the posts. Thus, the rails 3 are provided with side strips 3a, channel 3b, 25 holes 3c, reinforcing ears 3d, and rib portions 3e, corresponding to these members on the fence posts 2.

In order to secure the fence posts and fence rails to the fence, adapters 4 are provided, 30 which are in the form of sheet metal cups, having polygonal depressions 4a corresponding to the shape of the holes 1a, 2c, or 3c. These adapters 4 are provided with square openings 4b, which receive a square head portion 5a of a bolt 5, preferably a stove bolt. By placing a pair of these adapters over the 35 corresponding holes in the fence and fence-posts or rails, a bolt 5 may be inserted through the alined holes of the two adapters 40 and the nut 5b of the bolt may be tightened so as to hold the several members in position. This structure is illustrated in Fig. 7. In this case, the fence rail as well as the fence post is held by the bolt 5.

Where the fence rails extend over the side strips 3a of the fence posts, the rib portions 3b are cut away as shown in Figs. 1, 6 and 7.

The ear portions 1b, 2c, or 3d, are yieldable enough so that though all the openings 50 are of the same size, said ear portions of the various members of the fence may telescope within one another, as shown in Fig. 7.

It will be noted that the holes may be of any polygonal shape. The best shapes, however, are the 3-sided, 4-sided and 6-sided polygons.

By changing the proportions of the fence posts slightly, these posts may be mounted obliquely relative to the fence as shown in 55 Fig. 8. The fence posts 6, thus formed, are similar in construction to the fence posts 2, in that they are provided with side strips 6a, arranged to extend along alternate diagonal rows of the fence, and are separated 65 by a channel portion 6b. The side strips

as well as the channel portion may be provided with polygonal openings 6c, having marginal reinforcing ears 6d. In addition the outer margins of the side portions 6a may be provided with ribs which extend toward the fence as shown best in Fig. 9.

The fence post 6 is secured to the fence by the adapters 4 and bolts 5.

The channel portions 2b and 6b of the fence posts 2 and 6 form convenient means 75 for receiving the protruding ends of fence stakes 7 and 8 respectively.

The fence stake 7 may be in the form of a T-beam as shown in Fig. 6. Any suitable temporary means may be used to hold the fence in the desired position with the fence posts, and rails if desired, thereupon. The stakes 7 are then inserted in the channels 2b, and while retained in position by the channel 2b are driven into the ground. If 80 these stakes are made to fit snugly within the channels 2b, no provision need be made for securing them to said channels. Thus the fence posts and corresponding portion of the fence form a guide means for maintaining the stakes in their proper position for being 85 driven into the ground.

The same applies in the structure shown in Figs. 8 and 9, except that the stakes 8 fit better in the channels 6b, if they are in the 90 form of I-beam.

It can be seen that by using the fence posts to guide the stakes, particularly when the fence posts are inclined, that it is quite easy 100 to drive the stakes into the ground at the correct angle and correct location.

It will also be noted that with the fence posts set diagonally, the rails may be easily dispensed with, yet maintaining a rigid fence structure, as the upper portion of one rail 105 may overlap the bottom of the next.

Though I have shown and described a particular construction, combination and arrangement of parts and portions, I do not wish to be limited to this particular construction, combination and arrangement, but desire to include in the scope of my invention 110 the construction, combination and arrangement substantially as set forth in the appended claims.

Having thus described my invention, what I claim as new and desire to secure by Letters Patent is:

1. In a fence structure, a foraminous fence formed of sheet material, foraminous posts for said fence, portions of said posts arranged to lie contiguous to said fence, and a separate and independent securing means extending through certain alined openings in said posts and said fence.

2. In a fence structure, a foraminous fence formed of sheet material foraminous posts for said fence also formed of sheet material, and arranged obliquely across said fence and se-

curing means connecting said posts to said fence.

3. In a fence structure, foraminous fence formed of sheet material, foraminous posts for said fence also formed of sheet material and arranged obliquely across said fence, securing means connecting said posts to said fence, guide means associated with said posts, and fence stakes arranged to be inserted 10 in said guide means and slidably longitudinally therein.

4. In a fence structure, a fence formed of sheet material, said fence provided with a plurality of openings therethrough arranged 15 in rows, reinforcing ears bordering said openings, fence posts for said fence formed of sheet material and provided with a plurality of spaced apart openings therethrough, reinforcing ears bordering said openings, certain ear portions of said posts arranged to telescope with certain other ear portions of said fence, and separate and independent securing means adapted to extend through certain alined openings in said post and said fence.

25 5. In a fence structure, a fence formed of sheet material provided with a multiplicity of perforations, pointed projections bordering said perforations, fence posts formed of sheet material, also provided with a multiplicity 30 of perforations, pointed projections bordering said perforations, the certain pointed projections of said fence posts arranged to interlock with the pointed projections of said fence.

35 6. In a fence structure, a fence formed of flat sheet material and provided with a multiplicity of polygonal shaped perforations, pointed projections, bordering said perforations, fence posts formed of sheet material and having structural section, said fence posts provided with a multiplicity of polygonal shaped perforations, and pointed projections bordering all sides of said perforations, the projections of said fence posts arranged 40 to interlock with the projections of said fence.

45 7. In a fence structure, a fence formed of flat sheet material and provided with a multiplicity of polygonal shaped perforations, pointed projections bordering said perforations, fence posts formed of sheet material and having structural section, said fence posts provided with a multiplicity of polygonal shaped perforations, pointed projections bordering all sides of said perforations, the projections of said fence posts arranged to interlock with the projections of said fence, whereby certain corresponding perforations in said fence and said fence posts are alined, and separate means utilizing certain of said alined perforations for securing said fence to said fence posts.

55 8. In a fence structure, a fence formed of flat sheet material and provided with a multiplicity of polygonal shaped perforations,

pointed projections bordering said perforations, fence posts formed of sheet material and having structural section, said fence posts provided with a multiplicity of polygonal shaped perforations, and pointed projections bordering said perforations, the projections of said fence posts arranged to interlock with the projections of said fence, and stiffening ribs formed between the perforations in said fence. 75

9. In a fence structure, a foraminous fence formed of sheet material, foraminous posts for said fence, portions of said posts arranged to lie contiguous to said fence, foraminous rails for said fence arranged to extend between said posts, and securing means extending through certain alined openings in said fence, posts, and rails. 80

10. In a fence structure, a fence formed of sheet material provided with a multiplicity of perforations, projections bordering said perforations, fence posts formed of sheet material, also provided with a multiplicity of perforations, projections bordering said perforations, the certain projections of said fence posts arranged to interlock with the projections of said fence, fence rails formed of sheet material provided with a multiplicity of perforations, and projections bordering said perforations, the projections of said fence rails arranged to interlock with the projections of said fence or said fence posts. 90 95

11. In a fence structure, a fence formed of sheet material provided with a multiplicity of perforations, projections bordering said perforations, fence posts formed of sheet material, also provided with a multiplicity of perforations, projections bordering said perforations, the certain projections of said fence posts arranged to interlock with the projections of said fence, fence rails formed of sheet material provided with a multiplicity of perforations, projections bordering said perforations, the projections of said fence rails arranged to interlock with the projections of said fence or said fence posts. 100 105 110

12. In a fence structure, a fence formed of sheet material provided with a multiplicity of perforations, projections bordering said perforations, reinforcing means formed of sheet material provided with a multiplicity of perforations and having a structural section, said reinforcing means adapted to form the posts and rails of said fence, and means utilizing certain alined perforations of said fence and reinforcing means for securing the same together. 120 125

13. In a fence structure, a foraminous fence formed of sheet material, foraminous posts for said fence, portions of said posts arranged to lie contiguous to said fence, and a 130

securing means extending through certain alined openings in said posts and said fence, other portions of said posts arranged to form a guide means and fence stakes slidably mounted therein.

14. In a fence structure, a fence formed of sheet material provided with a multiplicity of perforations, projections bordering said perforations, reinforcing means formed of sheet material provided with a multiplicity of perforations and having a structural section, said reinforcing means arranged to extend obliquely across said fence, coupling means utilizing certain alined perforations of said fence and reinforcing means for securing the same together.

15. In a fence structure, a fence formed of sheet material provided with a multiplicity of perforations, projections bordering said perforations, reinforcing means formed of sheet material provided with a multiplicity of perforations and having a structural section, said reinforcing means arranged to extend obliquely across said fence, coupling means utilizing certain alined perforations of said fence and reinforcing means for securing the same together, guide means forming parts of said reinforcing means, and fence stakes slidably mounted in said guide means.

16. In a structure of the class described, a perforated wall forming member formed of sheet material, perforated reinforcing posts therefor having structural cross sections, a plurality of said perforations in said post and said wall forming member being in alinement, and separate means securing said posts to said wall forming member through said alined perforations.

17. In a structure of the class described, a perforated wall forming member formed of sheet material, a plurality of perforated reinforcing posts secured to said wall forming member, stake guides formed by said posts and wall forming members, and stakes arranged to slide in said stake guides.

18. In a structure of the class described, a perforated wall forming member formed of sheet material, a plurality of perforated reinforcing posts arranged diagonally upon said wall forming member, diagonally disposed stake guides formed by said posts and wall forming members, and stakes arranged to slide in said stake guides.

In testimony whereof, I have hereunto set my hand at San Diego, California, this 7th day of August, 1930.

WILLIAM K. MORRISON.
